UNITED STATES PATENT OFFICE.

EDWARD HOLMES AND BRITAIN HOLMES, OF BUFFALO, NEW YORK.

WINDLASS FOR COMPRESSING BARRELS.

SPECIFICATION forming part of Letters Patent No. 292,817, dated February 5, 1884.

Application filed January 29, 1883. (No model.)

To all whom it may concern:

Be it known that we, EDWARD HOLMES and BRITAIN HOLMES, citizens of the United States, residing in Buffalo, in the county of Erie and State of New York, have invented certain new and useful Improvements in Power-Windlass for Barrels, of which the following is a specification.

The object of this invention is to provide the means for drawing the free ends of the staves together after their opposite ends have been set up and secured within a truss-hoop, so that their edges will meet and be adapted to receive another truss-hoop for securing the staves in the form of a barrel-body which can be safely handled during the further operations required to complete the barrel, all of which will be fully and clearly hereinafter shown by reference to the accompanying drawings, in which—

Figure 1 is a side elevation, and Fig. 2 is a vertical section through line X X, Fig. 1.

A is the frame, which is supported in the usual way on legs a'.

B is a vertically-movable rack secured to the frame by a box, a², so that it can be moved vertically up or down.

a³ represents a pinion securely fastened to the shaft b, which is secured in suitable boxes, b' b², made in any well-known way. The outer end of the shaft b is provided with a pulley, b³, rigidly secured thereto. The box b² is fitted in vertical slideways c, made in any well-known way, so it will have an easy vertical movement up or down, and thereby impart a similar movement to the pulley b³.

c' is an arm jointed to the box b² by a pin, c², and to a foot step or treadle, c³, by a pin, d.

The rack B is provided with two arms, c⁴, jointed thereto at their lower ends by bolts d'. Their upper ends, d², are bent or formed as shown in Fig. 1, and are provided with rollers d³, which roll in guideways d⁴ for keeping them in position within the frame.

E represents an adjustable bar having a series of perforations, e', through either of which one of said bars is jointed to the top of each of the arms c⁴ by a pin or bolt, and each bar E is provided with a holding-piece, e², to which the ends of the cable e³ or its equivalent are rigidly fastened.

F represents the driving-pulley, arranged

to run in suitable bearings, f', which bearings are made vertically adjustable by means of the screws and jam-nuts f² f³. The driving-pulley shaft G is provided with a small pulley, g', the face of which is covered with leather g², or other similar equivalent material, for the purpose of increasing the friction between the pulleys b³ and g', when in contact. The object in making the driving-pulleys vertically adjustable is to allow for the wearing of the leather or other covering on the pulley g'. At the moment the edges of the staves of the barrel are brought together by the cable or truss-rope the movement of the compressing-force must cease, or either the barrel will be injured or the cable or truss-rope broken; hence the necessity of operating the machine by means of the friction between the pulleys d³ and g', which will give or slip when the staves are brought together, as above mentioned, and thereby prevent the breaking of the machinery. The pinion a³ gears into the rack B.

The operation of the invention will be easily understood. When the end of the barrel adapted to be operated upon, as hereinbefore mentioned, is placed within the truss-rope or cable e³ a pressure of the foot on the treadle brings the pulleys b³ g' in contact with sufficient force to operate the machine, so as to raise the rack B and bring the arms c⁴, which act together as a toggle-joint, into the position shown by the dotted lines i i' i² i³, in Fig. 1, thereby bringing the staves together so that a truss-hoop may be put on, as before mentioned. When the pressure is taken off the parts all resume their normal position, as shown in Fig. 1. It will be noticed that while using the machine the driving-pulley and friction-pulley g' are kept in motion by a belt arranged in the usual way.

In some cases the pulleys F and g' may be dispensed with and the driving-belt applied directly to the pulley b³ in such a manner as to slip when the necessary strain has been given. The pulley b³ would have to be provided with flanges, arranged in any well-known way, to prevent the belt from running off while slipping, but we prefer the arrangement above described.

In the drawings, we have shown a rack and pinion for operating the toggle-joint, but we

do not confine ourselves to the precise arrangement shown for giving such motion, as there are many other ways for giving the necessary reciprocating movements to said toggle-joint—for instance, an additional toggle-joint having an arm connecting it with a crank to a suitable mechanism on the driving-pulley, or by a small steam cylinder and piston of sufficient length to give the movements, or a screw connected thereto in any well-known way may be used for giving such movements.

Some of the advantages resulting from the employment of a toggle-joint are that the ends of the cable are drawn in opposite directions, so that the staves are all evenly and simultaneously moved together, thereby bringing them together more truly and with less danger of breaking any of them than if the strain all came from one side. Furthermore, a toggle-joint moves more quickly on the start, but slower and with increasing power as the motion proceeds, which also renders the staves less likely to break than if the power was applied from one side only. Besides the power increases as the resistance increases, just when it is required.

If desired, the parts E may in some cases be dispensed with and the cable connected directly to the parts d^2 of the toggle-joint levers.

We claim—

1. The pulley b^3 , secured to a shaft, b , having a pinion, a^3 , in combination with the rack B, toggle-joint c^4 , and cable c^5 , substantially as and for the purposes described.
2. The pulley b^3 , secured to a shaft, b , having a pinion, a^3 , in combination with the rack B, arms c^4 , adjustable perforated bars E, and truss cable or rope c^5 , substantially as set forth.
3. A windlass for barrels, consisting of the frame, the pulleys F g^4 , and the pulley b^3 , arranged in a shaft having a pinion, a^3 , and capable of a vertical movement, substantially as specified, in combination with the movable rack B, toggle-joint, arms c^4 , holding-bars E, and the cable or truss-rope, for the purposes described.
